UNITED STATES PATENT OFFICE.

FENTON FREDERICK STRATTON, OF EAST CROYDON, ENGLAND.

CARBURETOR.

Application filed November 16, 1921, Serial No. 515,518, and in Great Britain November 16, 1920.

The objects of this invention are to provide better means for feeding the correct relative proportions of liquid fuel and air to the engine, to better control the correct supply of mixture to the engine under all conditions of running, and to increase the efficiency of the apparatus in operation, and further to enable the carburetor to respond readily to sudden demands made upon it by the engine to enable it to accelerate quickly when called upon to do so.

And in order that my invention may be completely understood reference should be made to the accompanying sheets of drawings.

Fig. 1 is a sectional elevation of a carburetor constructed according to my invention.

Fig. 2 is a section of the carburetor on a line at right angles to the section shown in Fig. 1.

Fig. 3 is a plan view.

Fig. 4 is a horizontal section on the line X X of Fig. 2.

Fig. 5 is a sectional elevation of a modified form of my invention in which a separate pilot or auxiliary nozzle for slow running and starting is employed.

Fig. 6 is a horizontal section on the line Z Z of Fig. 5.

With reference to Figs. 1 to 6, the central cylindrical inner casing A is mounted upon a base H and formed with a circumferential flange or ring A¹ of larger diameter. Mounted upon the said flange A¹ and on either side thereof, are two outer cylindrical casings B and C, so arranged in respect to the central casing A, and the base H, as to form closed annular chambers B¹ and C¹ above and below the said circumferential flange A¹. The upper casing B, forming the outer wall of the chamber B¹, is provided with an outlet B², having a flanged joint of usual form for connecting the carburetor to the inlet manifold of the engine. The lower casing C is provided with a series of holes C² for the free admission of air to the lower annular chamber C¹. Wire gauze C³, of suitable mesh, is adapted to cover each of the holes C² in order to prevent the ingress of dust and dirt into the carburetor. The central cylindrical wall A is provided with two sets of ports located above and below the ring flange A¹, in such manner that the upper ports E, which are of rectangular form,

mixing chamber A² and the upper annular mixture chamber B¹ while the lower ports G, which are of triangular form, are adapted to place the lower annular air chamber C¹ in communication with the said chamber A² on the lifting of the piston valve.

The valve D is slidably mounted within the said central chamber A and is formed as a sleeve with a closing diaphragm D¹ and a ring of ports F situated in the said sleeve beneath the said diaphragm D¹, which are adapted to register with ports E formed in the wall of the chamber A. The said sleeve D¹ is of such length that its lower extremity is adapted to cover the triangular ports G and to uncover same on the said sleeve valve D being lifted. The ports E, F and G are so relatively situated that, on the sleeve valve D being lifted, the ports F will commence to register with the ports E slightly before the sleeve D¹ commences to uncover the air ports G.

The base H which is preferably formed integrally with the float chamber Q, of usual construction is formed with a cylindrical boss H² concentrically arranged to project within the chamber A². The boss H² is centrally bored to carry the nozzle I, which is preferably screwed into position, by means of the nut I³ from beneath the said boss H², and formed with a conical surface adapted to abut against a similar internal surface formed within the said boss H², in order to afford a fuel tight joint.

The liquid fuel is fed to the nozzle I from the float chamber Q by means of a duct J drilled in a projection H¹ formed on the under side of the base H.

Concentrically surrounding the nozzle I are two telescopic cylindrical sleeves L and K. The inner or fixed sleeve L which projects within and is secured to the boss H² of the base H, has drilled therein at suitable intervals along its length, rings of small orifices or outlet ports L¹. The rings of ports L¹ are so arranged one above the other that the outer telescopic sleeve K, the upper rim of which is secured to the diaphragm D¹ of the sleeve valve D, on being lifted, uncovers successively each ring of ports L¹ thus varying the depression upon the nozzle I in relation to the movement of the sleeve valve D.

Centrally arranged within the sleeve K and adapted to slidably project within the orifice I² of the nozzle I is a tapered needle O

so graduated as to vary the area of the orifice of the nozzle through which the liquid fuel is drawn, in relation to the position of the said sleeve D, to the diaphragm D¹ of which the said needle is attached. The upper end of the said needle O is formed as a bolt O² with a shoulder O¹ and a nut O³. The shoulder O¹ is adapted to engage the underside of the rim of the sleeve K and the bolt O² passes through a hole R¹, of slightly larger diameter than the said bolt O², in the diaphragm D¹ of the valve D, in such manner that the diaphragm D¹ is securely held between the upper side of the rim of the sleeve K and the nut O³.

Air is admitted to the chamber surrounding the nozzle I and enclosed by the sleeves K and L, by a short length of pipe T (see Fig. 2) screwed or otherwise secured in the base H and provided with a screw T² adapted to cover or uncover holes T¹ in the said tube T for the purpose of accurately adjusting the admission of air. The screw T² is provided with a milled head T³ to facilitate its action.

In the form of my invention shown in Figs. 1 to 4 the diaphragm D¹ of the sleeve valve D is constructed with a horizontal duct or channel R adapted to communicate with the chamber enclosed by the sleeves K and L through small holes or ports R⁴ (Figs. 4 and 5). The said duct R is also adapted to be placed in communication with the annular chamber B¹ through the medium of the ports E, a short horizontal channel R³ situated above and preferably parallel to the channel R, and a vertical channel R² connecting the two said parallel ducts or channels R, R³. In this manner the nozzle chamber enclosed within the sleeves K and L is placed in communication with the annular chamber B¹ when the sleeve valve D is at the lower extremity of its stroke. A fine threaded screw S formed with a conical lower end or needle S³ is mounted above and concentric with the vertical channel R² in such manner that the area of the passage through the said channel may be accurately adjusted. The said screw S is provided with a milled head S² and a locking nut and sleeve S¹ in order that the said screw S may be finely adjusted with the fingers.

The sleeve valve D is adapted to be reciprocated by the movement of a bell-crank lever N connected to the said valve D by a link M, one end of which is rotatably mounted upon a pin D² arranged in hollow bosses D³ diametrically formed on opposite sides of the upper end of the said sleeve valve D. The said bell crank lever N is pivotally mounted upon a bracket N¹ secured to the upper casing of the carburetor. The bracket N¹ is formed with a bridge piece N² through which an adjustable screw stop P is adapted to pass. The said screw P is

provided with a locking nut P¹ and is adapted to limit the maximum movement of the said lever N. Four bolts W pass through the annular chambers of the carburetor and serve to hold the said outer casings B and C and the central casing A firmly in position upon the base H.

When the sleeve valve D of the carburetor is at its lowest or closed position as shown in the drawings, the ports E and G are not in communication with the inner or mixing chamber A², the chamber surrounding the nozzle however is in communication with the annular chamber B¹ and is therefore open to the suction of the engine, causing a rich mixture of fuel and air necessary for slow running to be drawn from the carburetor. The relative proportion of fuel to air is adjusted by means of the screws S and T².

On the sleeve valve D being lifted the ports F commence to register with the ports E, thereby placing the chamber A² in communication with the annular chamber B¹ and the engine. At the same time the outer telescopic sleeve K uncovers the lower row of ports L¹ in the inner sleeve L placing the chamber A² in communication with the chamber surrounding the nozzle I, while the area of the nozzle orifice is increased due to the tapered needle being raised. The sleeve valve D still covers the air ports G causing an increased relative pressure to be exerted upon the nozzle I and consequently a momentary rush of fuel from the said nozzle resulting in a rapid acceleration of the engine.

On the sleeve valve D being further raised, the air ports G are uncovered and air is admitted to the mixing chamber, at the same time further rings of ports L¹ in the sleeve L are uncovered by the sleeve K, causing a less restricted passage for rich mixture from the nozzle chamber to the mixing chamber, in proportion to the increased volume of air admitted. The outlet of the duct or channel R³ is now raised above the port E and consequently ceases to function.

As the sleeve valve D is further raised, more air is admitted to the mixing chamber A², the ports F more completely register with the ports E to the annular chamber B¹, the outer sleeve K uncovers a further ring of ports in the sleeve L and the area of the orifice I² of the nozzle I is increased owing to the needle valve O lifting and allowing a freer passage of liquid fuel.

By this arrangement the relative quantities of fuel and air are constantly maintained in the most efficient proportion at any speed, while a very rapid acceleration is given to the engine when required.

With reference to Figs. 5 and 6 this form of my invention is constructed and functions in a similar manner to that described with reference to Figs. 1 to 4 with the ex-

ception that in lieu of the channels R , R^2 , R^3 , and R^4 , and the adjusting screw S in the sleeve valve D , a separate pilot or auxiliary nozzle is employed. This auxiliary nozzle 5 consists of a tube V of two internal diameters V^1 , V^6 , forming at their junction a conical shoulder V^5 . The tube V is screwed at V^3 into the base H in such position that the internal bore V^1 communicates with the 10 fuel passage J from the float chamber Q . The tube V passes through the annular air chamber C^1 , the flange A^1 and the annular mixture chamber B^1 and projects through the upper casing B , where it is held in position 15 by the nut V^2 , which also provides a gas tight closure. The internal diameter V^6 is provided with a fine internal thread at its upper end into which is fitted the screw S^1 , of an adjusting needle S , in such manner 20 that the conical end S^7 of the needle S may be screwed down towards the tapered shoulder V^5 , to adjust the area of the orifice for the passage of liquid fuel. The needle S is provided with a milled nut S^5 and a locking 25 nut S^6 . Above the shoulder V^5 are diametrically arranged holes or ports V^4 approximately in line with the ports E and which afford communication between the internal bore V^6 and the annular chamber B^1 . The 30 area of the said holes or ports V^4 is governed by the position of the needle S which covers or uncovers these said outlets. Air is supplied to the auxiliary nozzle through the 35 passages T^4 and T^5 (Fig. 6) and is adapted to be drawn across the jet through the outlets V^4 . The area of the air inlet channel T^4 is adjusted by means of the conical ended screw T^6 provided with a milled head T^8 and a locking nut T^7 .

40 On the sleeve valve D being at its lowest or closed position the ports E will be covered and the holes or outlets V^4 will be subjected to the full negative pressure thereby causing the liquid fuel in the bore V^1 to rise above 45 its normal working level and impinge upon the needle S^7 where it meets and mixes with the air flowing through the ports or outlets V^4 . This rich mixture of fuel and air is drawn into the engine and provides mixture 50 for slow running. The proportion of fuel to air is adjusted by means of the screws S and T^6 .

When the sleeve valve D is lifted and the

ports E opened the negative pressure in the annular chamber B^1 will fall, causing the liquid fuel in the bore V^1 to drop to its normal working level and the auxiliary nozzle will cease to function. 55

What I do claim as my invention and desire to secure by Letters Patent is:— 60

1. A carburetor for internal combustion engines comprising a mixing and control chamber, concentrically arranged with a central nozzle chamber, and surrounded by superimposed annular chambers, the lower 65 for the admission of air and the upper for the passage of the mixture, a nozzle within said nozzle chamber, a sliding valve for placing the annular chambers in communication with the mixing chamber, and means 70 for operating the sliding valve, said nozzle chamber comprising telescopic sleeves the inner of which is perforated and the outer of which is operatively connected to the sliding valve and moves therewith to uncover 75 the perforations of the inner sleeve for controlling the passage of the mixture from said nozzle chamber to the mixing chamber.

2. A carburetor for internal combustion engines comprising a mixing and control 80 chamber surrounded by superimposed annular chambers, the lower for the admission of air and the upper for the passage of the mixture, the mixing and control chamber having vertically spaced openings therein affording communication with the superimposed annular chambers, a sliding valve operable within the mixing and control chamber for placing the annular chambers into 85 communication with the mixing and control chamber, said valve having a horizontal partition intermediate its ends and openings therebeneath adapted to be placed in registration with the upper openings in the mixing and control chamber when the valve is 90 raised, a perforated sleeve secured within the mixing and control chamber, a sleeve carried by the valve and telescoping the first mentioned sleeve, the two sleeves forming a nozzle chamber, a nozzle extending 100 into said nozzle chamber, a needle depending from the valve partition for controlling discharge from the nozzle, and means mounted above the valve partition for raising and lowering the valve.

FENTON FREDERICK STRATTON.
